FLEXIBLE SHOE.

1,163,818.

Specification of Letters Patent. Patented Dec. 14, 1915.

Application filed August 5, 1915. Serial No. 43,901.

To all whom it may concern:

Be it known that we, GEORGE L. PIERCE and ANDES K. PETTERSON, citizens of the United States, residing at Brooklyn, New York, have invented certain new and useful Improvements in Flexible Shoes, of which the following is a specification.

Our object is to provide a flexible shoe of simple and economical construction, and it consists in the features and combination and arrangement of parts hereinafter described and particularly pointed out in the appended claims.

In the accompanying drawing Figure 1 is a plan view of a shoe embodying our invention; Fig. 2 is a plan view of a portion of the shoe and shank partly in section; Figs. 3 and 4 are detail sectional views; Fig. 5 is a view of the inner sole member.

In carrying out the invention, we employ an inner sole member 1 extending from the toe throughout the heel, thus providing an intermediate shank portion 2. This shank portion is split along its edges, as shown at 3, this split portion extending from the point *a* to the point *b*. The upper is fastened in the usual way to this inner sole around the ball of the foot. The upper at this portion is simply laid on the face of the inner sole, but at the shank portion of the shoe the edge of the upper is laid in to the slits extending along the edges of this shank portion, and is secured by a line of stitching back from the edges of the shank, as indicated at *c*. The edge of the upper previous to this stitching or, in other words, as it is laid in the split portion of the shank, is doubled upon itself, and the stitching is done as indicated in Fig. 2 at the right thereof. The flap or outer part *d* of the split part of the shank portion of the member 1 is then pressed down, as shown on the left of Fig. 2, and a line of stitching *e* is carried through this flap *d*, and the upper, and entirely through the member or inner sole 1, as indicated. This line of stitching *e* is also carried through the tap or outer sole, which may be suitably slotted to secure blind stitching at this point, and this line of stitching may be carried also around the outer heel to attach it to the sole portion. It will thus be seen that the upper is

fastened by nailing or pegging it to the face of the inner sole around the ball of the foot, but at the shank the edge of the upper is drawn in between the upper and lower portions of the edge of said shank formed by splitting it, and then the sewing is done, as above mentioned.

We claim as our invention:

1. A flexible shoe having an inner sole member extending from the toe and providing a shank portion between the ball of the foot and the heel, said shank portion being split along its edges, and an upper fastened to the face of the inner sole around the ball of the foot, and having its edge laid in the slit formed by splitting the edges of the shank portion, said upper being sewed with in the slotted portions of the shank, substantially as described. 60

2. In combination in a flexible shoe, an inner sole member having a shank portion, the latter being slotted along its edges longitudinally, an upper fastened to the face of the inner sole portion and having its edges laid within the slotted portion of the shank, a line of stitches passing through the outer flap of the split edge of the shank portion and through the edge of the upper, a tap sole, and a line of stitching extending through the split portion of the shank through the upper and also through the tap sole, the upper and the inner sole, substantially as described. 70

3. In combination in a shoe, an inner sole member including a ball portion, shank portion and heel portion, the shank portion being slotted along its edges longitudinally, a line of stitches securing the edge of the upper within the slits of the shank, a tap sole, and a heel, and a line of stitching passing through the shank and the edge of the upper, and also passing through the tap sole, the heel, and the inner sole, and through the interposed edge of the upper, substantially as described. 85

In testimony whereof, we affix our signatures in presence of two witnesses.

GEORGE L. PIERCE.
ANDES K. PETTERSON.

Witnesses:

E. L. STURGES,
FRANCIS G. COATES.
